(57) **CLAIM**

I claim the ornamental design for a masking film for vehicle, as shown and described.

DESCRIPTION

FIG. 1 is a surface view for a “masking film for vehicle” showing my new design,

FIG. 2 is a partial enlarged view of “2, 4” and “2, 3, 5” of FIG. 1,

FIG. 3 is a partial enlarged view of “3, 5” and “2, 3, 5” of FIG. 1,

FIG. 4 is a partial enlarged view of “2, 4” and “4” of FIG. 1; and,

FIG. 5 is a partial enlarged view of “3, 5” and “4” of FIG. 1.

1 Claim, 5 Drawing Sheets
